CLAIM

The ornamental design for a force applying end of a chiropractic adjusting instrument including body contact member and shank, as shown and described.

DESCRIPTION

FIG. 1 is a bottom perspective view of a force applying end of a chiropractic adjusting instrument including body contact member and shank showing my new design;

FIG. 2 is a side elevational view thereof;

FIG. 3 is a bottom plan view thereof, taken along line 3—3 in FIG. 2; and,

FIG. 4 is a top plan view thereof, taken along line 4—4 in FIG. 2.

The broken line illustration in FIGS. 1, 2, and 3 is for illustrative purposes only and forms no part of the claimed design.
